COMPRESSION REFRIGERATING MACHINE

Willy Hirche, Leopoldshain, Germany

Application September 4, 1936, Serial No. 99,436
In Germany September 24, 1935

3 Claims. (Cl. 62—115)

In refrigerating machines with compressor the oil must be conducted to the moving parts, yet prevented from accumulating in the system. According to the invention the circulation of the oil is regulated by a collector chamber formed on the evaporator. The oil collects in this container and is circulated through the system in freely distributed state with the refrigerant, in such a manner that the moving parts receive ample lubrication but no oil can accumulate in the system.

The refrigerant laden with lubricant is sucked into the crank case by the compressor and then forced to the condenser and back to the evaporator where the lubricant separates from the refrigerant by gravity before being again circulated through the system. As the crank case and the evaporator are directly connected by the feed pipe for the refrigerant the pressure in the crank case is the same as that in the evaporator.

An embodiment of the invention is illustrated by way of example in the only figure of the accompanying drawing.

The compressor comprises a crank case 2 with cylinder 1 extending therefrom. A piston 6 reciprocates in this cylinder 1 and has in its head a suction valve 5 adapted to establish communication between the space 3 of the cylinder and the crank case 2 during the suction stroke of the piston 6. The cylinder space 3 is closed by a pressure valve 4.

A feed pipe 7 communicates with the crank case 2 and a delivery pipe 13 extends from the cylinder space 3 below the pressure valve 4. The delivery pipe 13 extends to a condenser 14 from which a pipe 15 leads to an evaporator 8 filled with liquid refrigerant, an expansion valve 16 being arranged between the end of the pipe 15 and the evaporator 8. The evaporator is enlarged at its upper end to form a collector chamber 10 and the feed pipe 7 extends into this chamber. A layer of lubricant floats on the top of the refrigerant in the chamber 10 and the end 11 of the feed pipe 7 is bent upwards so that its extremity is above the level of the oil 9 in the chamber 10, holes 12 being provided in the pipe end 11 below the layer of the oil 9 floating on the lubricant.

During the downward stroke of the piston 6 in the cylinder 1 refrigerant and oil are drawn into the crank case 2 through the pipe 7 from the chamber 10 of the evaporator 8.

During the return or upward stroke of the piston 6 the pressure valve 4 closes and the suction valve 5 in the piston opens under the suction

produced in the cylinder space 3, thus the refrigerant laden with lubricant previously drawn into the crank case 2 passes through the valve 5 into the cylinder space 3.

When the piston 6 again descends the valve 5 closes and the refrigerant is compressed in the space 3 until the pressure valve 4 yields and allows it to pass out through the delivery pipe 13 to the condenser 14 and thence to the evaporator through the pipe 15 and throttle cock 16.

The lubricant passes with the refrigerant through the crank case and cylinder; it lubricates these parts but has no opportunity of collecting anywhere. On being returned to the evaporator it automatically separates therefrom and floats to the surface thereof owing to its lighter specific weight.

Thus the lubricant is continually circulated through the system with the refrigerant and all moving parts receive ample lubrication.

I claim:

1. A compression refrigerating machine with oil circulation, comprising in combination a compressor, a condenser, an evaporator and an expansion valve located in a plane entirely below the compressor and condenser and connected directly to the condenser, said compressor being of such construction whereby oil unrestrictedly flows therethrough, a single oil collecting chamber in the machine located in said evaporator at the upper end thereof and adapted to collect all the oil in circulation in the machine, and a common conduit between said compressor, condenser, evaporator and expansion valve adapted to convey the oil with the refrigerant through said compressor, condenser and expansion valve to said evaporator.

2. A compression refrigerating machine with oil circulation, comprising in combination a compressor, a condenser, an evaporator and an expansion valve located in a plane entirely below the compressor and condenser and connected directly to the condenser, said compressor being of such construction whereby oil unrestrictedly flows therethrough, a single oil collecting chamber in the machine located at the upper end of said evaporator in the direction of flow of the refrigerant and adapted to collect all the oil in circulation in the machine, and a common conduit between said compressor, condenser, evaporator and expansion valve adapted to convey the oil with the refrigerant through said compressor, condenser and expansion valve to said evaporator.

3. In a compression refrigerating machine in

which is utilized a lubricant which is immiscible with the refrigerant, a compressor, a condenser, an expansion valve and an evaporator connected directly in series, a single oil collecting chamber in the machine, said oil collecting chamber being located in said evaporator, said compressor having a compressor casing and a crank case forming an extension of said casing, a crank gear in

said casing, said compressor casing having an inlet above said crank gear, the oil being admitted with the refrigerant vapors into said crank case through said inlet to lubricate said gear and being immediately sucked off from said crank case with the refrigerant vapors.

WILLY HIRCHE.
